UNITED STATES PATENT OFFICE

HAIG SARAFIAN, OF NEW YORK, N. Y., ASSIGNOR TO NOVELITE, INC., OF NEW YORK, N. Y., A CORPORATION OF NEW YORK

DESIGN FOR AN ADVERTISING PANEL

Application filed June 4, 1929. Serial No. 31,544. Term of patent 14 years.

To all whom it may concern:

Be it known that I, HAIG SARAFIAN, a citizen of the United States, and residing at New York city, in the county of New York and State of New York, have invented a new, original, and ornamental Design for Advertising Panels, of which the following is a specification, reference being had to the ac-

companying drawings, forming part hereof.

The figure is a front view of the advertising panel.

I claim:

The ornamental design for an advertising panel as shown.

HAIG SARAFIAN.
